Primary Examiner—Ted Shooman*Assistant Examiner*—Nanda Bondade*Attorney, Agent, or Firm*—Keck, Mahin & Cate**[57] CLAIM**

The ornamental design for a CD-ROM jukebox, as shown and described.

DESCRIPTION

The FIGURE is a top, front and left side perspective view of a CD-ROM jukebox according to my invention; the right side is a mirror-image of the left side; the rear side and bottom are unornamented.
